(57) **CLAIM**

We claim the ornamental design for a product packaging, as shown and described.

DESCRIPTION

FIG. 1 is a front view of a product packaging showing our new design in an environment, the rear view being a mirror image thereof;

FIG. 2 is a top view thereof;

FIG. 3 is a bottom view thereof;

FIG. 4 is a front view of a product packaging showing our new design in another environment, the rear side being a mirror image thereof;

FIG. 5 is a top view thereof;

FIG. 6 is a bottom view thereof;

FIG. 7 is a front view of the product packaging of FIGS. 1-4 shown with a product example attached; and FIG. 8 is a rear view thereof;

FIG. 8 is a rear view thereof; and,

FIG. 9 is a perspective view of a product packaging of FIGS. 1-4.

The broken lines in the Figures are for illustrative purposes only and form no part of the claimed design.
